UNITED STATES PATENT OFFICE.

ARTHUR R. WOOLFOLK, JR., OF NEW YORK, N. Y., ASSIGNOR TO SQUARE D COMPANY, OF DETROIT, MICHIGAN, A CORPORATION OF MICHIGAN.

QUICK-BREAK DOUBLE-THROW SWITCH.

1,400,337.

Specification of Letters Patent. Patented Dec. 13, 1921.

Application filed July 10, 1918. Serial No. 244,179.

To all whom it may concern:

Be it known that I, ARTHUR R. WOOLFOLK, Jr., a citizen of the United States, residing in the city, county, and State of New York, have invented certain new and useful Improvements in Quick-Break Double-Throw Switches, of which the following is a full, clear, and concise description thereof.

My invention relates to quick break double throw switches generally. These switches may be of the inclosed type and one of the objects of my invention is to provide for improved external operation of said double throw quick break switch.

15 A further object of this invention is to provide improved means whereby an intermediate or neutral position may be assumed by the switch mechanism.

Other objects of this invention will in part 20 be apparent and in part be further described in the detailed description following.

One of the many possible forms which this invention may take is shown in the accompanying drawing, in which—

25 Figure 1 shows a longitudinal sectional elevation of the switch mechanism and casing, such section being taken on the line 1—1 of Fig. 2; and

Fig. 2 is a plan view of the switch mechanism with the cover of the casing open.

Referring in detail to the figures, it will be seen that the switch is inclosed in a casing 2 which includes the base portion and a hinged cover 3. Such cover has a recessed portion 4 to accommodate certain portions of the switch mechanism. It is to be understood, of course, that this cover may be locked in closed position by means of an apertured tongue 5 which passes through an opening in the cover 3 and is adapted to receive the bail or hook portion of a padlock or other suitable locking means. This metal casing is suitably insulated from the electrical parts of the switch mechanism by means of an insulating base 6 which is securely fastened to the base of the casing 2. Upon this insulating base is mounted a pair of contact members 7 which have pivotally mounted thereon knife blades 8 which are adapted to be thrown from one extreme position, as shown in the drawings, to the other extreme position in the usual manner of operating a double throw switch. These pivoted knife blades coöperate with stationary contacts 9 and 10 arranged at the extreme

limits of its motion. From these contacts 7, 9 and 10, suitable wires may extend and are adapted to be connected to these contacts by means of the connectors shown at 11. These connectors are of the tubular type having a flattened portion which is screwed to the contacts. These knife blades 8 are operated through the medium of a cross head 12, which in the example shown, is a metal rod which is suitably insulated from the knife blades by means of an insulating sleeve 13. These knife blades are fastened to this insulating sleeve 13 by means of clamping members or other suitable means, not shown. This cross head 12 has crank members 14 at either end which are pivoted in the sides of the casing in alinement with the pivots of the knife blades 8. It is, of course, obvious that these crank members 14 may be omitted.

The operating member for this switch mechanism comprises a horizontal portion 15 extending parallel to the horizontal portion of the cross head 12. This horizontal portion continues over and forms crank members 16 which are pivotally mounted in the sides of the casing. From one side an external handle 17 extends by which means this operating member 15 may be externally operated. The means for connecting the cross head 12 and the operating member 15 comprises a slotted spring link, the casing or rigid portion of which is shown at 18. In this link or casing is placed a spring 19 which is fastened to the operating member 15 and the cross head 12. This link is provided with a slot 20 which allows the operating member to have limited travel within the link. In the position shown in full lines in Fig. 1, the operating member 15 is resting in the lower portion of the slot 20 and the spring 19 is in contracted position. When this operating member through the medium of the external handle 17 is rocked upwardly, the spring 19 is extended and places stress upon the cross head 12 tending to withdraw the knife blades 8 from engagement with the contacts 9. However, the frictional engagement is sufficient to maintain these two members 8 and 9 in engagement until the operating member 15 strikes against the upper part of the slot 20 and positively initiates the withdrawal of the contacts 8 from engagement with the contacts 9, whereupon the spring 19 rapidly completes the withdrawal of these contacts

8 from the contacts 9. The switch mechanism then assumes the position shown in dotted lines, the link being indicated at 18' and the operating member at 15' and the cross head at 12'. In this position the link at its upper end has engaged the cam projection or lug 21. This serves to temporarily arrest the motion of the switch in its neutral position. Upon continued motion of the operating member the link is tilted to the position shown at 18'' because of the engagement of the cam or lug 21 with its upper portion. This rocks the cross head to the position shown at 12'' and thereafter the link slides free of the cam or lug 21 and the operating member 15 engages the lower portion of the slot and forces the cross head downward and causes the pivoted knife blades 8 to engage the contacts 10. It is, of course, understood that upon reverse operation of the switch the same action takes place as the one just described, as all of the parts are symmetrically arranged with respect to a vertical central transverse plane. The lug 21 is carried upon an arch shaped member 22 which may be ribbed to give added stiffness and may be secured upon the insulating base 6 in the manner shown. This particular arrangement of supporting member for the lug may be varied, however, within the scope of the invention.

It will be seen from the above description that a very simple quick break double throw mechanism has been provided, in which the sole connecting member between the operating member and cross head and knife blades consists of a spring link.

It will be further noted that this spring link controls the motion of the knife blades 8, as may be seen from the dotted illustration in Fig. 1.

It will further be noted that by means of the lug 21 there is a definite stop provided for the neutral position of the switch which would offer a slight resistance to the continued motion of the switch past its neutral position, and would, therefore, be of a decided value when it was intended to open the switch and leave it in such opened position.

It will further be noted that by means of this invention a quick break double throw switch has been provided which includes a minimum number of parts and that the parts thereof are very substantial and rugged and that the switch will be reliable in its opera-

tion and free from complicated constructions.

It will be understood that the detailed description and drawings are to be interpreted in an illustrative sense only, as it is intended that the invention shall be limited only as defined by the following claims.

I claim:

1. A quick break double throw switch comprising coöperating stationary and movable contacts, a cross head attached to said movable contacts, an operating member, a link intermediate said operating member and cross-head, and a cam member for tilting said link. 65

2. A quick break double throw switch comprising coöperating stationary and movable contacts, a cross head attached to said movable contacts, an operating member, a link intermediate said operating member and cross-head, a cam member for tilting said link, and means for supporting said cam member. 75

3. A quick break double throw switch comprising coöperating stationary and movable contacts, an operating member, a link intermediate said operating member and movable contacts, and means coöperating with said link and operating member to temporarily arrest the switch in its neutral position. 80

4. A quick break double throw switch comprising a base and coöperating stationary and movable contacts mounted thereon, an operating member, a link intermediate said operating member and movable contacts, means inclosing said operating member and said link in their complete movement from one to the other of their extreme positions, and means associated with said last-mentioned means to temporarily arrest the switch in its neutral position. 90

5. A quick break double throw switch comprising a base and two pairs of stationary contacts and a coöperating pair of movable contacts, an operating member for said movable contacts, a link intermediate said operating member and said movable contacts, resilient means associated with said link to obtain a quick break between said pair of movable contacts and said two pairs of stationary contacts, and means coöperating with said link and operating member to temporarily arrest the switch in its neutral position. 100

ARTHUR R. WOOLFOLK, JR.
